US00D620306S

(12) **United States Design Patent**
Tosdale et al.

(10) **Patent No.:** **US D620,306 S**
(45) **Date of Patent:** **** Jul. 27, 2010**

(54) **FOOD PAN**

(75) Inventors: **David R. Tosdale**, Manitowoc, WI (US);
Theresa M. Mayer, Sheboygan, WI (US)

(73) Assignee: **The Vollrath Company, L.L.C.**,
Sheboygan, WI (US)

(**) Term: **14 Years**

(21) Appl. No.: **29/345,670**

(22) Filed: **Oct. 20, 2009**

(57) **CLAIM**

We claim the ornamental design for a food pan, as shown and described.

DESCRIPTION

FIG. 1 is a top perspective view of an embodiment of the claimed design;

FIG. 2 is a front view thereof;

FIG. 3 is a right side view thereof;

FIG. 4 is a rear view thereof;

FIG. 5 is a left side view thereof;

FIG. 6 is a top view thereof; and,

FIG. 7 is a bottom view thereof.

The broken lines in the drawings are for illustrative purposes only and form no part of the claimed design.

1 Claim, 7 Drawing Sheets

See application file for complete search history.
